EXPANSIBLE PLUG-TYPE CLOSURE

Dallas R. Green, Hooper, Utah

Application June 27, 1950, Serial No. 170,593

4 Claims. (Cl. 220—24.5)

1

This invention relates to closures, and more particularly to a closure of the expansible plug type.

An object of this invention is to provide a closure which is particularly adapted for use with a tank including two spaced apart apertures in the top thereof, such as the tanks used in transporting and vending soft water.

Another object of this invention is to provide a closure for effecting a tight seal for the liquid-withdrawing apertures of a tank.

A further object of this invention is to provide a closure which is particularly adapted for use with a tank including two spaced apart apertures, the closure being easily and speedily attached to and detached from its position in closing relation with the apertures.

A still further object of this invention is to provide a closure of the expansible plug type which is simple in structure and relatively cheap to manufacture.

The above and still further objects and advantages of the invention will become apparent upon consideration of the following detailed description of the invention, when taken in conjunction with the accompanying drawings, wherein:

Figure 1 is a top plan view of the closure of the present invention supported on the top of a tank in closing relation with respect to a pair of spaced apart apertures provided in said top;

Figure 2 is a side elevational view of the closure of the present invention;

Figure 3 is a side elevational view of the closure of the present invention, shown in section, as supported in the spaced apart apertures provided in the top of the tank in position to be locked for effecting a tight fluid seal; and

Figure 4 is a sectional view taken along the line 4—4 of Figure 1, showing the closure in the locked position for effecting the tight fluid seal for the spaced apart apertures of the tank.

Referring now more particularly to the drawings, wherein like reference numerals have been used throughout the several views to designate like parts, there is shown the closure of the present invention, generally designated by the reference numeral 10, as applied to a tank 11 including two spaced apart apertures 12, 13 in the top 14 thereof.

The closure 10 embodies a fixed base plate 20 which is adapted to overlie the apertures 12, 13 in the top 14. Disposed on one side of the plate 20 adjacent each of its ends are the washers 21, 22, which are fabricated of any suitable sponge rubber material. Disposed transversely of the plate 20 and overlying the washer 22 is a first stopper 23 which is fabricated of any hard rubber material, and has one end abutting against the adjacent face of the washer 22. Disposed contiguous to the other end of the stopper 23 is

a bearing plate 24 which abuts against the adjacent end face of the washer 23.

Similarly, there is provided a second stopper 25 positioned in spaced parallel relation with respect to the first stopper and having one end abutting against the adjacent face of the washer 21. Abutting against the other end face of the stopper 25 is a bearing plate 26.

Disposed in confronting and contacting relation with respect to the other side of the fixed plate 20 is a movable plate 27. Extending through the assembly of the fixed plate 20, the washers 21, 22, the stoppers 23, 25 and the bearing plates 24, 26, and the movable plate 27 are the bolts 28, 29 which have their heads 30, 31 abutting against the bearing plates 24, 26, and have their threaded ends 32, 33 projecting beyond the non-confronting face of the movable plate 27. Engaging the threaded end 32 of the bolt 28 is a nut 34 which maintains the assembly of the stopper 23 and associated elements in the desired positions with respect to each other. Similarly, there is provided a nut 35 on the threaded end 33 of the bolt 29 for maintaining the assembly of the stopper 25 and associated components in the desired relation.

Disposed contiguous to the non-confronting face of the movable plate 27 is a hand-actuable lever 36 which is pivotally supported contiguous to one end by means of the pin 37, the other end of the lever 36 being provided with a handle 38. Extending through a slot 39 provided in the movable plate 27 is a camming element 40 which has one end formed integrally with or fixedly secured to the lever 36 contiguous to the pivot 37 and has the other end ground for engagement with the fixed plate 20. As clearly shown in Figure 3, the lever 36 is normally disposed at right angles with respect to the movable plate 27 with a side edge of the camming element 40 resting upon the fixed plate 20. Upon manually grasping the handle 38 and effecting a counterclockwise movement of the lever 36, the curved surface of the camming element 40 is brought into bearing engagement with respect to the fixed plate 20 to thereby urge the movable plate 27 away from the fixed plate 20. The extent of the movement of the movable plate with respect to the fixed plate is predetermined by the length of the camming element utilized.

In actual use, the lever 36 is disposed in its position normal to the movable plate 27, whereupon the stoppers 23, 25 can be inserted within the openings 12, 13 of the top 14 of the tank. The inserted and supported position of the stoppers is clearly shown in Figure 3. Upon manually grasping the handle 38, and effecting a counterclockwise rotation, the plate 27 is urged away from the plate 20 which simultaneously compresses stoppers 23, 25 and urges their peripheries into tight sealing engagement with

the bounding walls of the apertures. The locked position of the closure is clearly shown in Figures 2 and 4.

To remove the closure from its supported position in sealing engagement with respect to the apertures 12, 13, it is merely necessary to grasp the handle 38 and impart a clockwise movement to the lever 36, whereupon the camming element is restored to the position shown in Figure 3. The stoppers 23, 25 can then be removed from the supported position within the apertures 12, 13 and be applied at some later time or utilized in conjunction with another tank.

The device of the present invention is especially useful where it is necessary to effect tight fluid seals rapidly and where it is desired to utilize the same closure for sealing tanks having standard, spaced apart, fluid-withdrawing openings, such as those utilized in transporting and vending water for drinking and commercial purposes.

Although only one embodiment of the closure of the present invention has been described, it is readily apparent that numerous modifications can be made without departing from the spirit of the invention set forth in the appended claims.

What I claim is:

1. A closure for a tank of the type having two spaced apart liquid-withdrawing apertures, said closure comprising a fixed base plate adapted to overlie said apertures, a first laterally expansible cylindrical stopper disposed transversely of said plate contiguous to one side thereof and having one end connected to said plate, a second laterally expansible cylindrical stopper disposed in spaced parallel relation with respect to said first stopper and connected to said one side of the plate, said stoppers being arranged to be simultaneously insertable within said apertures, a movable plate disposed in confronting and contacting relation with respect to the other side of said fixed plate, and means operatively connected to said movable plate and to the other end of each of said expansible stoppers and arranged to exert longitudinal compression on the stoppers to expand said stoppers into tight engagement with the bounding walls of said apertures in response to the movement of said movable plate out of confronting and contacting relation with respect to said fixed plate.

2. A closure for a tank of the type having two spaced apart liquid-withdrawing apertures, said closure comprising a fixed base plate adapted to overlie said apertures, a first laterally expansible elongated cylindrical stopper disposed transversely of said plate contiguous to one side thereof and having one end connected to said plate, a second laterally expansible elongated cylindrical stopper disposed in spaced parallel relation with respect to said first stopper and connected to said one side of the plate, said stoppers being arranged to be simultaneously inserted within said apertures, a movable plate disposed in confronting and contacting relation with respect to the other side of said fixed plate, means operatively connected to said movable plate and to the other end of each of said expansible stoppers and arranged to exert purely longitudinal compression on the stoppers to expand the stoppers into tight engagement with the bounding walls of said apertures in response to the movement of said movable plate out of confronting and contacting relation with respect to said fixed plate, and hand-actuable means carried by said movable plate and engageable with said fixed plate for effecting the move-

ment of said movable plate to said position out of confronting and contacting relation and for maintaining the latter in said position.

3. A closure for a tank of the type having two spaced apart liquid-withdrawing apertures, said closure comprising a fixed base plate adapted to overlie said apertures, a first laterally expansible elongated cylindrical stopper disposed transversely of said plate contiguous to one side thereof of having one end connected to said plate, a second laterally expansible elongated cylindrical stopper disposed in spaced parallel relation with respect to said first stopper and connected to said one side of said plate, said stoppers being arranged to be simultaneously inserted within said apertures, a movable plate disposed in confronting and contacting relation with respect to the other side of said fixed plate, means operatively connected to said movable plate and to the other end of each of said expansible stoppers and arranged to exert purely longitudinal compression on the stoppers to expand the stoppers into tight engagement with the bounding walls of said apertures in response to the movement of said movable plate out of confronting and contacting relation with respect to said fixed plate, and hand-actuable means carried by said movable plate and engageable with said fixed plate for effecting the movement of said movable plate to said position out of confronting and contacting relation and for maintaining the latter in said position, 15

30 and for maintaining the latter in said position, said hand-actuable means comprising a lever disposed exteriorly of said movable plate and pivotally supported on the latter, and a camming element projecting through said movable plate having one end secured to said lever and having the other end engageable with said fixed plate.

4. A closure for a tank of the type having two spaced apart liquid-withdrawing apertures, said closure comprising a fixed base plate adapted to overlie said apertures, a first laterally expansible elongated cylindrical stopper disposed transversely of said plate contiguous to one side thereof and having one end connected to said plate, a second laterally expansible cylindrical elongated stopper disposed in spaced parallel relation with respect to said first stopper and connected to said one side of said plate, said stoppers being arranged to be simultaneously insertable within said apertures, a movable plate disposed in confronting and contacting relation with respect to the other side of said fixed plate, and means operatively connected to said movable plate and to the other end of each of said stoppers and arranged to exert purely longitudinal compression on said stoppers to expand said stoppers into tight engagement with the bounding walls of said apertures in response to the movement of said movable plate out of confronting and contacting relation with respect to said fixed plate, 45 said means including respective bolts extending through said movable and fixed plates and said stoppers and respective washers on said bolts bearing on the other ends of said stoppers.
